DESIGN FOR A SIGN

Ray H. Baker, Detroit, Mich.

Application September 14, 1936, Serial No. 64,854

Term of patent 7 years

To all whom it may concern:

Be it known that I, Ray H. Baker, a citizen of the United State of America, residing at Detroit, in the county of Wayne and State of Michigan, have invented a new, original, and ornamental Design for a Sign, of which the following is a specification, reference being had therein to the accompanying drawing forming a part thereof, wherein:

The dominant feature of my design consists in the provision of a body portion simulating wings in appearance, and in the provision of a portion centrally of the wings simulating a propeller.

I claim:

The ornamental design for a sign substantially as shown and described.

RAY H. BAKER.
